W. T. Criswell.

ATTORNEY

UNITED STATES PATENT OFFICE.

JOSEPH M. ANGELETTI, OF NEW YORK, N. Y.

REFILLABLE PENCIL.

Application filed November 26, 1923. Serial No. 677,003.

This invention relates more particularly to a class of writing devices.

My invention has for its object primarily to provide a pencil in which graphite lead is preferably used for writing and marking purposes, and which is of a form having a magazine adapted to hold a number of strips or pieces of the lead so that when each lead is consumed it may be replenished from within the pencil instead of requiring the new lead to be inserted in the pencil as is incident to the requirement of a number of ordinary types of pencils of this class, it being well known that owing to the fragility of such strips of lead they are very susceptible of being broken during the inserting process. The invention consists essentially of a tubular casing divided into a rear compartment and a forward compartment or magazine for holding a number of strips of marking lead. On the magazine end of the casing is a cap which is removable for allowing access into the magazine, and in this cap is an opening or outlet through which the marking lead is caused to protrude for use. Within the casing is a grooved bar for holding a single strip of the marking lead, and this bar leads from the outlet of the cap, through the magazine and into the rear compartment. Extending from part of the wall of the grooved bar to the opposed part of the casing is a deflecting flange against which the leads in the magazine will move when the casing is revolvably swung, and in turn one of the leads will move into the groove of the bar when the groove is empty.

Other objects of the invention are to provide in the grooved bar a rod or feed propeller which is slidably adjustable toward and from the cap for causing the marking lead to be adjustably fed through the outlet of the cap; to provide in the rear compartment rotative means having a spiral groove engaged by the feed propeller so that said means when rotated will cause the propeller to move in the grooved bar toward and from the cap for adjusting the marking lead outwardly of the outlet of the cap when it is desired to use the pencil for writing; and a further object of the invention is to provide a refillable pencil of a simple, efficient and durable construction which may be made in any appropriate size and shape.

With these and other objects in view, the invention will be hereinafter more fully explained with reference to the accompanying drawing forming a part of this specification in which similar characters of reference indicate corresponding parts in all the views, and will then be pointed out in the claims at the end of the description.

In the drawing, Figure 1 is an elevation of one form of refillable pencil embodying my invention.

Fig. 2 is a detail sectional view taken on the line 2—2 of Fig. 1.

Fig. 3 is a sectional view taken through the grooved bar used in the pencil.

Fig. 4 is an elevation of a slightly modified form of the pencil.

Fig. 5 is a detail sectional view taken on the line 5—5 of Fig. 4.

Fig. 6 is a sectional view taken on the line 6—6 of Fig. 2, and

Fig. 7 is a sectional view taken on the line 7—7 of Fig. 2.

The pencil has a casing 10 which may be of any appropriate shape and size, though the form of the casing illustrated has a tubular or cylindrical wall 11. Interiorly of the casing 10 at the central part of its wall is a removable partition or circular plate 12 dividing the casing into a forward compartment or magazine 13 and a rear compartment 14. The open forward end of the magazine portion of the casing 10 is preferably exteriorly threaded, and on these threads is removably screwed the threaded end 15 of a cap, as 16. The cap 16 is tubular and may be of substantially a cone-shape with one end of its passage disposed through the apex of the cap to provide an outlet 17 for marking lead, as 18, when it is desired to use the pencil for marking purposes. By removing the cap 16 from the casing 10 in the magazine 13 may be placed a suitable number of the leads 18, and each lead is preferably in the form of a strip of graphite, such as is commonly used in pencils of this class. The form of the casing, shown in Figs. 1 and 2, has in its central part a transverse opening, as 19, which leads into the rear compartment 14 at the partition 12, while in the form of the casing, shown in Figs. 4 and 5, this opening is dispensed with. The rear end part of the casing may be interiorly threaded, as at 20, and extend-

ing lengthwise of the interior of the casing from the cap 16 to the threads 20 is a bar 21 having a lengthwise groove 22.

The groove 22 of the bar 21 is of a size to accommodate only one of the strips marking leads 18 for being slidably moved toward and through the outlet 17 of the cap 16 of the casing. The grooved bar 21 passes through an opening in the dividing partition 12, and this partition is soldered or otherwise fixed to the bar. Extending from part of the wall of the grooved bar 21 in the magazine 13 as well as abutting against the partition 12 may be a flange 23 which terminates at an opposed part of the inner face of the wall of the casing 10, and on this flange is a short lug, as 24, which is disposed in a hole, as 25, provided in the wall of the casing in proximity to the cap 16. The grooved bar 21, and flange 23 are preferably made of yielding spring metal, and the lug 24 is of a size so that when the bar and the flange are assembled in the casing the bar will yield sufficiently to allow the lug to be admitted into the casing and sprung into the hole 25 for holding the grooved bar in a stationary position in the casing. The grooved bar 21 is of considerably smaller diameter than the diameter of the interior of the casing. The space in the magazine surrounding the grooved bar may thereby hold a relatively large number of the marking leads 18. The flange 23 is also of a width so that its free edge is in close proximity to the wall of the casing, and when it is desired to charge the groove of the bar 21 with one of the strips of marking lead the casing is swung to make approximately a half-turn. The lead in the magazine will then be moved against the flange 13 so that when the casing is slightly revolved reversely one of the strips of the marking lead will move into the groove 22 of the bar. Leading from the end of the grooved bar 21 at the cap 16 may be a tubular tip, as 26, of a length and diameter so that it removably extends through the passage of the tubular cap 16, and the passage of the tip 26 is of a diameter to receive each of the strips of the marking lead so that the strip may be readily forced through the tip and outwardly of the outlet 17 of the cap 16, but will frictionally hold the strip of lead sufficiently to prevent it from tending to accidentally fall out of the tubular tip. Serving to cause the strip of marking lead in the groove of the bar 21 to be adjustably moved through the tubular tip 26 and outwardly of the cap 16, in the grooved bar is a slidably feed propeller or rod 27. This feed rod is of greater length than the combined length of the magazine 17 and the tubular tip 26 of the grooved bar 21 so that the feed rod may be moved in the rear compartment 14 and in the magazine toward and

from the cap 16. When the feed rod 27 is moved toward the cap the strip of marking lead 18 seated in the groove of the bar 21 will be moved into and outwardly of the tip 26 and outwardly of the cap 16.

The feed rod 27 is adjustably moved back and forth in the grooved bar 21 by means of a rotary element, as 28, which is preferably composed of a strip of wire bent in the form of a spiral spring having spaced convoluted members, as 29, and the space between the convolution provide a spiral groove, as 30, extending throughout the length of the element. The rotary element is of a length approximately similar to the length of the rear compartment 14 of the casing 10, and the element surrounds the part of the grooved bar 21 and feed rod 27 in the rear compartment as well as being of a diameter to allow of being freely rotated. On the feed propeller or rod 27 is a lug 31 which is movably seated in the spiral groove 30 of the rotary element 28 so that when the element is revolved accordingly the lug 31 will likewise move in the groove 30 and the feed rod will then be moved in the grooved bar 21 toward and from the tubular tip 26.

In the form of the pencil illustrated in Figs. 1 and 2, the threaded end 20 of the casing 10 may be closed by an exteriorly threaded cap, as 32, which may be of a form for carrying a block of erasing rubber, as 33. The rear end of the grooved bar 21 and rear end of the rotary element 28 may movably abut against the cap 32. In the rear compartment 14 of the casing at the opening 19 is a wheel, as 34, which is rotatably mounted on the grooved bar 21 at the dividing partition 12 of the casing, and the forward end of the rotary spiral element 28 is fastened, at 35, to this wheel. The wheel 34 is of a diameter so that part of its outer edge protrudes through the opening 19 of the casing, and by rotating this wheel the rotary element 28 will be revolved for moving the lug 31 and the feed rod 27, as above explained.

In the form of the pencil, shown in Figs. 4 and 5, the threaded end 20 of the casing may have a threaded sleeve, as 36, screwed therein, and in this sleeve is rotatably held the annular flange or neck, as 37, of a cap, as 38, disposed exteriorly of the rear end of the casing. In the cap may be provided an erasing rubber, as 39. The rear end of the grooved bar 21 and rear end of the rotary spiral element 28 are seated in the rotatable sleeve 36, and the element 28 is fastened, at 40, to the cap 38 so that by revolving the cap 38 and sleeve 36 the rotary element 28 will be revolved for adjustably moving the lug 31 and the feed rod 27 also as hereinbefore explained.

In the foregoing description, I have embodied the preferred form of my invention.

but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:-

1. In a pencil as characterized, the combination with a casing having a removable tip, of a magazine in the casing adjacent the tip to receive marking leads, a grooved bar in the magazine having a tubular tip protruding through the tubular tip of the casing, said grooved bar having an internal diameter slightly larger than each of the leads and the bar being of considerably less diameter than the inner diameter of the magazine to provide a space for passage of the leads from the magazine into the groove of the bar, and a flange of approximately the length of the magazine extending from one of the edges of the groove of the bar to the casing, said flange having a lug protruding through an opening in the casing.

2. In a pencil as characterized, the combination with a casing having a removable tubular tip on its forward end and having a rear compartment, and having a magazine in the casing adjacent the tip to receive marking leads, of a groove bar in the magazine extending into the passage of the tubular tip and extending into the rear compartment of the casing, the groove of said bar being slightly larger than each of the leads and the bar being of considerably less diameter than the inner diameter of the magazine to provide a space for passage of the leads from the magazine into the groove of the bar, a flange of approximately the length of

the magazine extending from one of the edges of the groove to the casing, a propelling rod in the groove of the bar, a rotatable spiral wire in the rear compartment of the casing surrounding the groove bar and the propelling rod and having spaced convolutions, and a lug protruding from the propelling rod and movably disposed between the convolutions of the spiral wire.

3. In a pencil as characterized, the combination with a casing having a removable tubular tip on its forward end and having a rear compartment, and having a magazine in the casing adjacent the tip to receive marking leads, of a grooved bar in the magazine extending into the rear compartment of the casing and having a tubular tip protruding through the tubular tip of the casing, said grooved bar having an internal diameter slightly larger than each of the leads and the bar being of considerably less diameter than the inner diameter of the magazine to provide a space for passage of leads from the magazine into the groove of the bar, a flange of approximately the length of the magazine extending from one of the edges of the groove of the bar to the casing, means securing the flange to the casing, a propelling rod in the groove of the bar, a rotatable spiral wire in the rear compartment of the casing surrounding the grooved bar and the propelling rod and having spaced convolutions, a lug protruding from the propelling rod and movably disposed between the convolutions of the spiral wire, and means operative exteriorly of the casing for rotatably adjusting the spiral wire to move the propelling rod in said grooved bar.

This specification signed and witnessed this 24th day of November, A. D., 1923.

JOSEPH M. ANGELETTI.
